UNITED STATES PATENT OFFICE.

HARRY B. HILLS, OF RIVERTON, NEW JERSEY, ASSIGNOR TO MARINE DECKING & SUPPLY CO., OF PHILADELPHIA, PENNSYLVANIA, A CORPORATION OF DELAWARE.

DECK CONSTRUCTION.

1,292,466.

Specification of Letters Patent. Patented Jan. 28, 1919.

Application filed November 19, 1918. Serial No. 263,195.

To all whom it may concern:

Be it known that I, HARRY B. HILLS, a citizen of the United States, and a resident of Riverton, in the county of Burlington and 5 State of New Jersey, have invented a new and useful Improved Deck Construction, of which the following is a specification.

In the construction of ships, the steel decks of which are to have applied thereto a 10 sheathing material of a cementitious nature, it is necessary to secure to a deck a multiplicity of steel clips so formed as to effect a bond between the sheathing material and the deck. It is customary to drill and 15 tap a deck at regular intervals to receive bolts with which the clips are secured to place. Since the steel plates forming a deck are relatively thin such drilling and tapping penetrates the deck plates thus impairing 20 the same in that they are not watertight. As compartments therebelow frequently contain oil, water and other materials it is essential that leakage be reduced to a minimum.

It is an object of the present invention to 25 overcome the above described disadvantageous features and provide a deck construction in which a plastic sheathing material may be bonded to a steel deck of a ship without perforation of the deck whereby the 30 same is rendered unimpaired and watertight. Another object of the present invention is to not only provide for such improved deck construction, but to accomplish the same in a manner both quicker and 35 cheaper than by present unsatisfactory methods of construction.

The invention consists of the improvements hereinafter described and finally claimed.

40 The nature, characteristic features and scope of the invention will be more fully understood from the following description taken in connection with the accompanying drawings forming part hereof, and in 45 which:—

Figure 1, is a fragmentary view in cross-section of a ship's hull illustrating the improved deck construction embodying features of the invention in application thereto.

50 Fig. 2, is a similar view drawn to an enlarged scale and illustrating details of construction.

Fig. 3, is a top or plan view of Fig. 2, with the deck sheathing removed; and

55 Fig. 4, is a fragmentary view, partly sec-

tioned, illustrating further details of construction.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings, 10 designates 70 the hull structure of a ship and 11 the athwart pieces, the deck-plates being designated 13. 14 designates a compartment beneath the deck-plates. These parts may be of varied construction as is well known in the art of ship-building. To the imperforate deck-plates 13, which are of relatively thin steel, and overlap as shown, are applied 75 clips for effecting a bond between the sheathing material 15 and the ship's deck. In practice these clips are spaced at regular intervals in staggered relation, care being exercised however that no clips are placed over the lapping portions of the deck-plates 13. These clips are elongated and narrow, and 80 are formed from a single piece of thin metal, having a depressed, central portion 16 terminating in raised angular extensions 17. The portion 16 may be apertured as shown 85 in the drawings. According to the present invention attachment of these clips to the deck-plates 13 is accomplished by means of arc welding as at 18, see Figs. 3 and 4. It will be observed that the clips so welded to 90 the deck plates are secured along the longitudinal edges of that portion of a clip which is depressed. This serves to prevent lateral movement of a clip. When the clips employed have an apertured depressed portion, they are additionally secured by means 95 of arc welding as at 19 as clearly illustrated in Fig. 2. It will be observed that the metal employed in effecting the weld fills a clip aperture and may be flowed over the 100 depressed portion of a clip to provide a head thus forming a rivet-like connection. With the clips in place as above described, sheathing material 15, which may be of any desired 105 form of cementitious mixture, may be laid upon the deck-plates. In this connection it 110

is to be noted that the clips are so formed as to readily bond the cementitious mixture to the deck-plates. It is to be further noted that since the ship's deck is imperforate, thus being watertight, leakage to a compartment 14 therebelow containing water, oil or other material, is reduced to a minimum. The above described deck construction, in addition to being efficient and possessing commercial value is cheaper and may be more quickly constructed than by present methods of deck construction hereinbefore referred to.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

What I claim is:

1. In a deck construction of the character stated, the combination of a ship having an imperforate deck, a compartment therebelow, a plurality of clips arc welded to the upper face of said deck in a manner to preclude lateral movement of the clips and a cementitious sheathing material for said deck.

2. In a deck construction of the character stated, the combination of a ship having an imperforate deck, a compartment therebelow, a plurality of clips disposed in staggered relation with respect to the upper face of said deck and arc welded thereto in a manner to preclude lateral movement of the clips and a cementitious sheathing material for said deck.

3. In a deck construction of the character stated, the combination of a ship having a deck made up of imperforate, overlapping, thin, metallic plates, a compartment therebelow, a plurality of clips disposed in staggered relation with respect to the upper face of said deck so that a clip does not come

above the lapped portion of said plates, said clips being arc welded to said plates and a cementitious sheathing material for said deck.

4. In a deck construction of the character stated, the combination of a ship having an imperforate deck, a compartment therebelow, a plurality of apertured clips arc welded to the upper face of said deck the metal employed in effecting the weld penetrating the aperture of a clip, said clips being further arc welded to the deck in a manner to preclude lateral movement of a clip and a cementitious sheathing material for said deck.

5. In a deck construction of the character stated the combination of a ship having an imperforate deck, a compartment therebelow, a plurality of apertured clips arc welded to the upper face of said deck the metal employed in effecting the weld penetrating the aperture of a clip, said clips being further arc welded to the deck in a manner to preclude lateral movement of a clip and a cementitious sheathing material for said deck.

6. In a deck construction of the character stated the combination of a ship having an imperforate deck, a compartment therebelow, a plurality of apertured clips disposed in staggered relation with respect to the upper face of said deck and arc welded thereto the metal employed in effecting the weld penetrating the aperture of a clip, said clips being further arc welded to said deck in a manner to preclude lateral movement of a clip and a cementitious sheathing material for said deck.

7. In a deck construction of the character stated the combination of a ship having a deck made up of imperforate, overlapping, thin, metallic plates, a compartment therebelow, a plurality of apertured clips disposed in staggered relation with respect to the upper face of said deck, so that a clip does not come above the lapped portions of said plates and are welded to said plates adjacent a clip aperture and further are welded to said plates in a manner to preclude lateral movement of a clip and a cementitious sheathing material for said deck.

In testimony whereof, I have hereunto signed my name.

HARRY B. HILLS.
